(57) **CLAIM**

The ornamental design for an index card style planner leaf, as shown and described.

DESCRIPTION

FIG. 1 is a front view of an index card style planner leaf showing our new design;

FIG. 2 is a rear view thereof;

FIG. 3 is a plan view of the relative positioning of the front and rear index card style leafs represented in FIGS. 1 and 2; and,

FIG. 4 is a side elevation view of the index card style planner leaf of FIG. 1.

The stippling is being used to represent surface color contrast.

Certain text portions and the spiral binding are illustrated in phantom for environmental purposes only and form no part of the claimed invention.
